UNITED STATES PATENT OFFICE.

JOSEPH S. THOMPSON, OF MILL VALLEY, CALIFORNIA.

ELECTRIC-CIRCUIT-BREAKING SWITCH.

1,380,438.

Specification of Letters Patent. Patented June 7, 1921.

Application filed September 29, 1920. Serial No. 413,557.

To all whom it may concern:

Be it known that I, JOSEPH S. THOMPSON, a citizen of the United States, and a resident of Mill Valley, in the county of Marin and 5 State of California, have invented a new and useful Improvement in Electric-Circuit-Breaking Switches, of which the following is a specification.

My invention relates to switches for handling high voltage electric current and my object is first, to secure a simple automatic overload release circuit breaking switch for outdoor installation, and second, to arrange the tripping mechanism of this switch so 15 that it is supported solely on the line insulators necessary to support the contact and blade portions of the switch.

I attain these objects by the device illustrated in the accompanying drawing in 20 which Figure I is a side elevation of a single pole switch complete, Fig. II is a view of the switch in the open position, and Fig. III is a partly sectional view of the tripping coil, latch, plunger and contact.

Similar letters refer to similar parts throughout the several views.

In my design 1 is a metal base, 2 is a fixed projecting pin, 3 is a pin so mounted on the base (1) as to permit a rocking motion to 30 be imparted to it by the shaft 4, the projecting pin (2) of the base (1) and rocking pin (3) supporting the insulator 5 and 5'. On the insulator (5) is supported by suitable means a projecting member or plunger face, 35 6, which may be of insulating material, and a contact member 7. If convenience required, the contact and other portions supported on insulator (5) could be made up in one piece. Supported on insulator (5') is a 40 plunger chamber 8, in which is carried the plunger 9, and the plunger spring 10, supporting a contact 11, a coil housing, 12, and the coil 13, mounted in such position over the plunger (9) that by means of a latch 14, it 45 can release the plunger permitting the spring (10) to force the plunger out and pushing the rocker unit supported on pin (3) outward, gravity completing the travel of the unit to the point where a suitable stop 15, 50 checks its movement, thus opening the switch. It will be seen that by extending

the shaft (4) and mounting other units on it, a multipolar switch can be made, and that the releasing of any one of the tripping latches will accomplish the opening of all 55 the poles of the switch. A suitable handle 16, mounted on the shaft (4) can be operated to close the switch, the projecting member (6) pressing back the plunger (9) until it is engaged by the latch (14). It will 60 also be seen that the tripping mechanism of this switch is mounted on the line insulators used to support the blade and contact, which insulators can be similar to those used throughout the rest of the line, and that 65 it does not require insulated rods or extra insulators for conveying the tripping movement.

What I claim is:

1. In an electric switch, a plunger engaging face and a switch blade on a rocker insulator, and a contact clip, a spring actuated plunger, a releasing latch and actuating series coil on a fixed insulator, the rocker insulator plunger face capable of being operated to force back the plunger into a latched position and the plunger capable of forcing away the rocker insulator plunger face, and with it the switch blade upon the release, through a predetermined flow of current 80 through the series coil, of the plunger releasing latch. 70

2. In an electric switch, a plunger engaging face of insulating material, and a switch blade on a rocker insulator and a contact clip, a spring actuated plunger, a releasing latch and actuating series coil on a fixed insulator, the rocker insulator plunger face capable of being operated to force back the plunger into a latched position and the plunger capable of forcing away the rocker insulator plunger face, and with it the switch blade upon the release, through a predetermined flow of current 85 through the series coil, of the plunger releasing latch. 90

In witness whereof, I have hereunto set my hand this 20th day of September, 1920.

JOSEPH S. THOMPSON.

Witnesses:

VIOLA M. HANSEN,
JAS. A. THOMPSON.
